(57) **CLAIM**

The ornamental design for a water filter, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top view of a water filter according to our new design;

FIG. 2 is a bottom view thereof;

FIG. 3 is a top perspective view thereof; and,

FIG. 4 is a right side view thereof, a left side view, front side view, and rear side view being identical to the right side view.

1 Claim, 4 Drawing Sheets
